[57] **CLAIM**

The ornamental design for a connector for framing system, as shown.

DESCRIPTION

FIG. 1 is a top plan view of a connector for framing system embodying my new design, the bottom being a mirror image;

FIG. 2 is a side elevational view thereof;

FIG. 3 is an end elevational view taken from the right of FIG. 1;

FIG. 4 is an end elevational view taken from the left of FIG. 1;

FIG. 5 is an enlarged perspective view thereof.

FIG. 1

FIG. 2

FIG. 3

FIG. 4

FIG. 5
